UNITED STATES PATENT OFFICE.

RICHARD SMITH, OF PHILADELPHIA, PENNSYLVANIA, ASSIGNOR TO MACKELLAR, SMITHS & JORDAN, OF SAME PLACE.

DESIGN FOR TYPE.

Specification forming part of Design No. 5,056, dated June 27, 1871.

To all whom it may concern:

Be it known that I, RICHARD SMITH, (assignor to MACKELLAR, SMITHS & JORDAN,) of the city and county of Philadelphia, Pennsylvania, have invented and produced a new and original Design for Printing-Type.

The nature of my design is fully represented in

the accompanying typographic impressions, to which reference is made.

I claim as my invention—

The design for printing-type, as shown.

Witnesses: RICHARD SMITH.
